UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR A TASSEL-PENDANT FOR LIGHTING-FIXTURE ORNAMENT.

48,156.

Specification for Design.

Patented Nov. 16, 1915.

Application filed June 21, 1915. Serial No. 35,461. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Tassel-Pendant for Lighting-Fixture Ornament, of which the following is a specification, reference being had to the accompanying drawing, forming part thereof.

Copies of this patent may be obtained for five cents each, by addressing the "Commissioner of Patents, Washington, D. C."

The figure is a front view of a tassel pendant for lighting fixture ornament, showing my new design.

I claim:

The ornamental design for a tassel pendant for lighting fixture ornament, as shown.

CHARLES E. JONES.
